UNITED STATES PATENT OFFICE

2,685,951

MULTIPLE COIN-OPERATED VENDOR

Clarence F. Rogier, Chicago, Ill.

Application October 22, 1948, Serial No. 55,943

3 Claims. (Cl. 194—10)

1

This invention relates to a multiple coin operated vendor. More specifically, it relates to a device which will accept the deposit of any one of three coins, will energize a dispenser to eject an article and return change equal to the difference between the coin deposited and the price of the article.

It is an object of the invention to provide a vendor which can be economically manufactured.

Another object of the invention is to provide a vendor which is simple yet rugged.

A further object of the invention is to provide a simple means for returning multiple coins as change.

Yet another object of the invention is to provide a simple means for deflecting coins from the magazine when the latter is full.

Still another object of the invention is to provide means for preventing jackpotting of the dispenser in the event that a coin switch should stick closed.

Another object of the invention is to provide means, operable in series by a coin requiring multiple coins in change, for operating the coin ejector a multiple number of times.

A further object of the invention is to provide means to insure the required number of actuations of the coin ejector.

Another object is to prevent emptying the coin magazine in the event a coin switch is held closed.

These and other objects of the invention will become apparent from a study of this specification and the drawings which are attached hereto and made a part hereof, and in which:

Figure 1 is an elevation of the vendor showing the slug rejector, the magazine loading and unloading means and the coin and slug return chute.

Figure 2 is a section of the vendor taken on the line 2—2 of Figure 7 showing the coin handling and ejecting means and the coin rejection relays.

Figure 3 is a bottom view of the device of Figure 1 showing the coin ejection means, the reject chute and the chute leading to the safe.

Figure 4 is a sectional view taken on the line 4—4 of Figure 2 showing the coin reject chute, the coin ejection slides and the slide jam cut-out switch.

Figure 5 is a sectional view taken on the line 5—5 of Figure 2 showing the quarter and dime chutes, the dime and quarter responsive switch and the slide locking relay.

Figure 6 is a sectional view taken on the line 6—6 of Figure 2 showing the slug rejector in con-

2

junction with the nickel reject relay, the nickel magazine and its loading chute, the low level magazine switch, the nickel chute and delivery switch and the magazine overflow chute.

5 Figure 7 is a sectional view taken substantially on the line 7—7 of Figure 2 showing the quarter chute, the pay-out switch actuators, the quarter delaying mechanism and the slide locking means.

Figure 8 is a sectional view taken on the line 10 8—8 of Figure 2 showing the change return mechanism, the slide jam cut-out switch and the coin return chute.

Figure 9 is an enlarged sectional view of the 15 slide structure and the slide jam cut-out switch taken on the line 9—9 of Figure 4.

Figure 10 is a sectional view taken on the line 10—10 of Figure 5 showing the nickel chute and magazine, the nickel overflow chute, the dime and quarter chutes and the dime and quarter responsive mechanisms.

20 Figure 11 is a sectional view taken on the line 11—11 of Figure 5 showing the nickel magazine, the magazine low level switch, the coin return chute, the combined dime and quarter chute, the dime and quarter responsive mechanism and the pay-out and ejection slides in conjunction with the slide jam cut-out switch and the slide locking relay.

Figure 12 is a wiring diagram. 25 Referring now to Figures 1, 2, 5, 6, 7 and 12, the numeral 1 represents a channel-shaped frame which has fixed to it a fuse clip 3 having a time fuse 5, a nickel reject relay 7 having a blocking member 9 and a dime and quarter relay 11 having a blocking member 13 to enter the quarter chute and a blocking member 15 adapted to enter the dime chute. The relays, when they are energized, hold the members 9, 13 and 15 out of the chutes and, when deenergized, enter the chutes 30 to deflect coins to the reject chute as will appear below.

35 A slug rejector 17 is suitably positioned by pins 19 in the upper portion of the frame and may be any of the commercially available structures such as that disclosed in the patent numbered 2,0654,425 issued to John Gottfried.

40 As is well understood in the art, any of three coins may be inserted in the rejector at the point 20 and each coin will follow a different predetermined path to arrive at the positions N, D and Q shown in Figure 2. The N and Q positions are side by side while the D position is parallel to but behind the Q position.

45 A reject chute 21 (Figures 1, 2, 3, 4, 8, 10 and 55 11) is fixed to the bottom plate 23 by screw 25 and

is hooked to channel 1 by ear 21. This chute extends up to the bottom of the rejector adjacent position R (Figures 1 and 4), to which position all slugs and rejected coins are guided by the rejector. A suitable return trough (not shown) will receive the coins from chute 21 and make them accessible to the depositor. The coins blocked by the members 9, 13 and 15 are also returned to this position.

The coin chutes and operating mechanisms are built as an integral unit and mounted in the frame and on the bottom 23 by suitable bolts.

As shown, particularly in Figures 2, 6 and 10, the nickel passes from position N through a chute 29, which is slotted on both sides at 31, and the actuating wire 33 of the nickel switch 35 is projected through the slots so that it will be actuated by the passage of a nickel to close the switch. The switch starts the delivery cycle of the dispensing machine.

The chute has additional slots 37 below 31 and is notched at 39 from the lower end. A pair of ears 41 extend out from the wall of the chute and a lever 43 is pivoted in the ears. The lower end of the lever enters the notch 39 and lies in the path of the coins while the upper end carries a deflector 45 which may enter the slots 37 but is normally held out by weight 47.

The chute 29 has its lower end positioned to discharge into the coin pay-out tube 49. A loading chute 51 projects from the tube through the front cover 53 of the case so that the tube may be initially loaded with nickels.

A normally closed switch 55 is positioned at the base of the tube and has a seeker 57 which is normally positioned in the tube. When the coins reach a predetermined level, which should be at least that of four nickels, the seeker is forced out of the tube and the switch is opened.

An overflow coin chute 59 is positioned adjacent the nickel tube and empties at 60 into the coin safe (not shown). It will be seen from Figures 2, 6 and 10 that any nickels striking deflector 45 will be projected laterally through the opening 62 into overflow chute 59 and will be discharged by it into the safe.

Thus when the pay-out tube is full the last coin will stand on edge, will lie against the lower end of lever 43 and position the deflector 45 in chute 29 so that additional nickels will be projected into chute 59. As soon as the supply in the tube is lowered so that the last coin passes the end of lever 43, the deflector will be removed from chute 29 by weight 47.

A pair of slides 61 and 63 are disposed under the pay-out tube and are confined for longitudinal motion by the frame 1 and suitable guides 65 (Figures 3 to 9, and 11). A hole 67 is formed in slide 61 which is normally positioned in alignment with a hole 69 in slide 63. The latter is open at all times to an elongated orifice 71 in the base 23.

A pair of ears 73 (Figures 2, 4, 8, 9 and 11) are bent up from one end of slide 61 and one end of a bell crank 75, which is pivoted to the frame at 77, is connected thereto by slot 79. The armature 81 of a solenoid 83 is connected at 85 to the other arm of the bell crank. Springs 87 connected to the frame and to ears 73 normally hold the slide in the left-hand position (Figure 9), while the armature, when energized, moves the slide to position the hole 67 in alignment with the pay-out tube 49 so that a nickel may enter the hole. When the solenoid is deenergized, the springs 87 retract the slide and align hole 67 with 75

holes 69 and 71 so that the coin will pass from the machine into a suitable return chute where it will be available to the customer.

A normally open, slide jam cut-out switch 89 has its actuator 91 disposed to ride on the bell crank which, in the normal position (Figure 2), holds the switch closed. As soon as the solenoid moves away from the normal position the switch will open for a purpose to be described below.

The left end of the lower slide 63 is perforated at 93 and a headed pin 94 (Figs. 3, 9 and 11) having a reduced shank is extended through the opening 93 and through a slot 96 in the bottom 23. Springs 97, having one end hooked in ears 98 bent up from the slide 63 and the other end hooked into the frame, serve to hold the slide in its normal left-hand position (Fig. 11). A projection 99, turned upward out of the lower slide, limits the travel of the upper slide 61 to the left (Fig. 11). The left end of the lower slide also extends to the front (Figs. 2, 4, 8, 10 and 11) and an ear 100 is turned upward to receive a stud 101, which in turn serves as a pivot for the lever 102. A torsion spring 103 is mounted upon a projecting end of the stud and normally maintains the lever in a horizontal position. The right-hand end of the lever is bent upward, as indicated by numeral 104, to be engaged by a thumb and another projection 105 extends upward and locks against the base of the mounting bracket 107 for the switch 55. The lock may be released by downward pressure on the lever 102, after which both slides may be moved to the right to align the holes 67 and 69 with the magazine 49 and permit all the nickels to fall into the coin return trough. It will be noted that the projection 99 of the lower slide will bear against the left end of the upper slide during the movement to the right.

Referring now to Figures 2, 5 and 7, it will be seen that the position D at which the dime is discharged from the slug rejector 17 is behind the quarter position Q.

A chute 109 is disposed below this position and joins or merges with the quarter chute 111 at a point above the last quarter switch, which will be described later.

The chute 111 is disposed below the position Q to receive quarters from the rejector and terminates in the chute 59 so that coins falling therethrough will be deposited in the safe.

Four sets of longitudinal slots 113, 115, 117 and 119 are formed from top to bottom in the front and rear walls of the chute. The rear wall of the dime chute 109 also carries a slot 119. Levers 121, 123, 125 and 127 are pivotally mounted on a guard 129 and each projects through a corresponding set of slots. Each lever is pivoted to a parallel bar 131.

A pair of ears 133, 135 are bent out from the chute 111 and pivotally support a lever 137 having three fingers 139, 141 and 143 formed thereon which are adapted to enter pairs of notches 145, 147 and 149 in the chute. These fingers serve to retard the quarters prior to actuating levers 123, 125 and 127. The lever 137 has an actuator 151 mounted at the lower end, said actuator comprising arms 153 and 155 mounted at right angles to each other and adapted to be engaged by an upturned ear 157 on the end of slide 61.

Each time the slide moves to the right (Fig. 11), the arm 155 will be actuated to move fingers 139, 141 and 143 into their notches so that they will prevent the passage of a coin in the chute

and upon retraction of the slide, arm 153 will be contacted to retract the fingers. Since the axis of the levers 137 and actuator 151 is inclined, the weight of the actuator will normally retract the fingers, but in case it fails to retract the slide will do so.

A bracket 159 (Figs. 2, 5 and 10) mounted on guard 129 carries the normally open switch 161 which controls the delivery mechanism. As shown in Figure 5, the actuating wire 163 of switch 161 lies under the pin 165 on the parallel bar 131 so that a downward movement of the bar and its pin will close the switch. The spring in the switch will return the bar to its normal position when the pressure on it is relieved. The passage of a quarter through chute 111 will actuate levers 121, 123, 125 and 127 in succession. The passage of a dime through chute 109 will actuate lever 127.

A relay 167 is mounted by a bracket 169 to the frame. When deenergized, the armature 171 of the relay will engage the ear 157 on slide 61 on its return stroke under the action of springs 87 for a purpose to be described.

Wiring diagram

The vending machine and dispenser are connected to a source of preferably 110 volt A. C. current represented by the mains 173 and 175.

Main 173 is extended to one side of the 5¢ only lamp 187; to one side of each of the delivery switches 35 and 161; to one side of the slide locking relay 167; to one side of the normally open switch 177 of the delivery relay 181 and to the center pole of the normally closed shut-off switch 183 and its companion switch 185.

Main 175 is extended to one side of the empty lamp 189; to fuse 3; to the reject relay 7; to one side of the normally open switch 193 controlled by the relay; through the fuse 3 to the pay-out solenoid and to one side of the normally closed, jam cut-out switch 89.

This main is also extended to the other side of the slide locking relay 167; to the delivery relay 181; to the magazine motor 197 and to the cup drop motor 199.

The 10¢ and 25¢ reject relay 11 has a normally closed switch 201 and switches 203 and 205 which have a common center pole so that 203, which is normally closed, will be opened when normally open switch 205 is closed.

The delivery relay has a second normally open switch 207. The level of cups in the magazine 209 from which cups are being dropped operates a normally closed switch 211 which is held open when the level of cups in the magazine is above a predetermined level but closes when this level is passed.

An empty switch comprises two switches 213 and 215 having a common center pole. Switch 213 is held closed as long as the level of cups in any magazine is above the switch operator or as long as the magazine is indexing but opens when enough cups have been ejected to bring the level below the switch operator. The latter lies slightly below the level of the operator for switch 211. Switch 215 is closed at the same time that switch 213 is opened.

It will be seen that the slide locking relay is normally connected across the mains 173—175 so that it is energized as long as the power supply is on. This pulls its armature 171 out of the path of ear 157 on slide 61 and permits a full ejection stroke when required.

If there are nickels in the magazine 49, switch 5 will be closed and

Circuit A will be set up from main 175, through slide jam cut-out switch 89, line 225, 5¢ only switch 55, line 227, 10¢ and 25¢ reject relay 11, line 229, empty switch 213, lines 231, 221, shut-off switch 183 to main 173.

Should the nickel magazine level fall below a safe level, switch 55 will open and relay 11 will be deenergized to reject dimes and quarters.

Circuit B from main 175, 5¢ reject relay 7, lines 223, 229, switch 213, lines 231, 221, switch 183 to main 173 energizes the 5¢ relay and conditions the machine to accept nickels.

15

Nickel operation

Assuming that the cup dispenser magazines are filled and that a nickel is deposited, nickel delivery switch 35 will be closed momentarily to 20 establish

Circuit C from main 173 through line 219, delivery relay 181 to main 175.

The relay closes switches 207 and 177. The former closes a holding circuit through the relay 25 as follows:

Circuit D from main 175 through delivery relay 81, switch 207, line 221, shut-off switch 183 to main 173.

The relay is thus held energized after the 30 switch 35 is reopened.

Switch 177 closes the circuit to the cup drop motor as follows:

Circuit E from main 173, through switch 177, line 233, cup drop motor 199 to main 175.

35 This motor rotates cam 235 which opens switch 183 and closes switch 185 to establish a holding circuit for motor 199 as follows:

Circuit F from main 175 through motor 199, lines 233, 237, switch 185 to main 173 and the 40 motor continues to run until switch 183 is remade and 185 is broken by cam 235.

Since circuit D is controlled by switch 183, this circuit is broken, as are the circuits A and B through the reject relays, so that all coins inserted during the cycle will be returned to the 45 depositor.

The cup drop motor also controls the rest of the dispensing apparatus to drop the cup, fill it with the required product and restore the functioning parts, which are not shown, to normal for the next cycle.

The closing of switch 183 reenergizes the reject relays to receive another coin. The delivery relay is, of course, not reenergized until another 50 coin is deposited.

Dime operation

Assuming that the next coin inserted is a dime, the 10 and 25¢ delivery switch 161 is closed once and reopened. This sets up a circuit as follows:

Circuit G from main 173 through switch 161, line 239, switch 205 which is held closed by the 60 10¢ reject relay, lines 241, 219, delivery relay 181 to main 175 and sets up the same circuits as did the closure of the nickel switch 35 to dispense a product.

However, since the switch 183 is broken almost instantaneously with the closure of switch 161, the reject relay 11 will be deenergized while switch 161 is still made; and consequently, switch 70 203, on being closed, will set up.

Circuit H from main 173 through switch 161, line 239, switch 203, line 243, solenoid 83 to 75 main 175.

The slide 61 is thus actuated and one nickel is ejected from the magazine.

Quarter operation

In the event a quarter is deposited, the switch 161 is closed and reopened four times to secure four actuations of the slide and the return of four nickels.

The first closure of the switch 161, of course, closes the circuit H to secure the dispensing of one portion of the product. Since the series of coin switch closures is completed long before cam 235 reconditions switch 183, there is no danger of more than one dispensing operation being caused.

It should be noted that in order to prevent a too rapid operation of the switch 161, due to a too rapid passage of the coin down chute 111, the fingers 139, 141, 143 are moved into position in the chute upon each initial stroke of the slide 61 and thus catch and hold the coin after its passage of the switch actuating lever immediately above. The fingers are withdrawn upon return of the slide and the coin is released to operate the next lever. This is accomplished four times to secure the return of four nickels.

Indexing

Should one of the stacks of cups 245 fall below a predetermined minimum level, the switch 211 is closed to establish.

Circuit J from main 175 through magazine motor 197, line 247, switch 211, line 249, line 237, switch 185 to main 173.

The magazine is indexed to bring a fresh stack of cups in position and such stack reopens the switch to break circuit J.

It should be noted that since the indexing is controlled by switch 185, it can occur only during the dispensing cycle.

The operator for switches 213, 215 is set slightly below the level of the operator for switch 211 so that when the cups in the stack from which cups are being dispensed fall below the latter operator, the magazine motor will be started but only while switch 185 is closed. If all of the stacks in the magazine have been depleted, the switch 211 will not reopen; consequently, the magazine will index but only during each succeeding dispensing cycle and cups will be dropped by it until the level of one stack falls below the operator for switches 213, 215 whereupon switch 213 is opened and 215 is closed.

Switch 213 breaks circuits A and B to reject all coins and stop the rotation of the turret.

Switch 215 closes.

Circuit K from main 175 through empty light 189, line 251, switch 215, lines 231, 221, switch 183 to main 173.

Nickels only

If, at any time, the supply of nickels in magazine 49 should fall below a predetermined level which is at least four nickels, switch 55 will be opened to break circuit A and deenergize the 10 and 25¢ relay 11. This closes switch 201 to close

Circuit L from main 175 through switch 193

(which is held closed by 5¢ relay 7), line 253, switch 201, line 255, 5¢ only lamp 187 to main 173.

Thus the product may be secured by depositing nickels which are accumulated in magazine 49 and when sufficient nickels have accumulated to close switch 55, circuit A is reenergized and circuit L deenergized so that quarters and dimes will be accepted.

Protective features

As soon as the slide 61 is moved away from its normal position (right-hand position, Fig. 9), the slide jam cut-out switch 89 is opened. This de-energizes circuit A and the 10 and 25¢ relay.

Thus should the slide jam away from the normal position, no further change requiring coins could be deposited.

A second possibility is that if the 10 and 25¢ switch 161 fails to reopen due to stuck contacts, a stuck coin or other causes, the solenoid would remain energized and it would be impossible to return change. By breaking circuit A, no further coins will be accepted.

In this case, also, the time fuse 3 will blow in about one minute to prevent injury to the solenoid.

In any of the above events, there is nothing which prevents operation of the machine by means of a nickel.

In the case of the second possibility mentioned above in which the switch 161 is jammed, it would be possible, by repeatedly making and breaking the power supply (before the fuse is blown) as by pulling a plug or a main switch, to actuate the solenoid and pay out, one by one, all of the nickels in the magazine.

In order to prevent this, the slide locking relay 167, which is connected directly across the mains, is provided. As soon as the power supply is interrupted, the armature 171 moves into the path of ear 151 of slide 61 and prevents the slide from being returned by its springs far enough to eject the nickel which it holds. Bleeding of the magazine is thus prevented.

Operation

The deposit of a nickel secures the dispensing of one portion of the product in a cup; the deposit of a dime secures the product and the return of a nickel in change; the deposit of a quarter secures the product and four nickels in change.

Failure of the supply of nickels for coin return lights the "Use 5¢ only" lamp and sets the 10 and 25¢ rejector so that any coins of this denomination are returned to the depositor.

Sticking of the 10 and 25¢ switch or jamming of the pay-out mechanism effects the same result. In either, the machine may be operated by the insertion of nickels.

Failure of the cup supply sets the rejectors in both the nickel and the dime and quarter chutes and prevents acceptance of all coins. It also lights the "Empty" lamp.

While the vendor is shown and described in connection with a cup drop type of dispenser, it is obvious that it may be applied to any dispensing apparatus whether of the bottle, package or other type, since all that is necessary for the vendor to do is to energize the delivery relay of such a machine. This relay then controls the cycle of the dispensing machine. Some provision is usually made in the cycling apparatus or otherwise for deenergizing the reject relays so that an additional coin cannot be inserted until the cycle is completed.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What I claim to be new and desire to protect by Letters Patent of the United States is:

1. In a vending machine, the combination of a coin magazine, a coin ejecting element therefor, a switch, means defining a coin path, a number of switch actuating means disposed at predetermined stations along the path of the coin for successive operation to effective position in response to the passage of a coin, coin holding means disposed between adjacent stations, said holding means being movable to and from holding position to hold a coin between said stations, and means including said switch responsive to each actuating means when it is in its effective position for moving the holding means to holding position to delay the passage of the coin, said moving means comprising said coin ejecting element.

2. In a vending machine, the combination of a switch, means defining a coin path, a number of switch actuating means disposed at predetermined stations along the path of the coin for successive operation to effective position in response to the passage of a coin, coin holding means disposed between adjacent stations, said holding means being movable to and from holding position to hold a coin between said stations, a coin magazine, a coin ejecting element operable to and from a position under the magazine to eject a coin therefrom, means controlled by the switch for operating the element and means connecting said operating means to move said holding means to and from holding position to delay the passage of the coin.

3. In a vending machine, the combination of a

switch, means defining a coin path, a number of switch actuating means disposed at predetermined stations along the coin path for successive actuations to effective position by the passage of a coin, coin holding means disposed between adjacent stations to hold a coin between said stations, means mounting said holding means for movement to and from coin holding position, a coin magazine an actuatable coin ejector associated with the magazine for ejecting a coin therefrom upon each ejector actuation, means operable by said switch to actuate said ejector and means connecting said ejector for moving said holding means to and from coin holding position.
